Primary Examiner — Catherine A Tuttle(74) Attorney, Agent, or Firm — Neal, Gerber & Eisenberg LLP(57) CLAIM

The ornamental design for a golf tee, as shown and described.

DESCRIPTION

FIG. 1 is a front perspective view of a golf tee embodying my new design;

FIG. 2 is a top front, perspective view thereof;

FIG. 3 is a top plan view thereof;

FIG. 4 is a bottom plan view thereof; and,

FIG. 5 is a side view thereof, the other side view, as well as front and rear views being identical thereto.

The broken lines form no part of the claimed design.
